Patented June 20, 1922.

Inventor

Aniceto R. Visitacion.

By

Attorney John Watson.

UNITED STATES PATENT OFFICE.

ANICETO R. VISITACION, OF BROOKLYN, NEW YORK.

TOY.

1,420,505.

Specification of Letters Patent. Patented June 20, 1922.

Application filed October 4, 1920. Serial No. 414,607.

To all whom it may concern:

Be it known that I, ANICETO R. VISITACION, a citizen of the United States, and resident of Brooklyn, in the county of Kings 5 and State of New York, have invented certain new and useful Improvements in Toys, of which the following is a specification.

This invention relates to toys, and has for an object the provision of a device of novel 10 and simple construction which is durable, inexpensive and automatic in its operation; a further object being to provide a plaything which is adapted to afford a high degree of amusement for children, and which is automatic in its operation having life-like movements imparted by simple mechanical means.

In carrying out my invention I employ an oscillating miniature figure representation of a person, animal or other animate object, 20 said figure having swinging arms and legs, and an oscillating head, means for mounting the figure, traction means for supporting the device, means operated by said traction, means for transmitting movement to the figure, and sounding devices carried by the figure, all as hereinafter fully described and specifically set forth in the appended claims.

In the accompanying drawings forming part of this specification, Figure 1 is a side 30 view of my improved toy.

Fig. 2 is an edge view, parts of the structure being broken away and parts shown in sectional elevation.

Fig. 3 is a fragmentary side view of parts 35 of the device.

Fig. 4 is an edge view of the traction wheel forming part of the device; and

Fig. 5 is a fragmentary side view of one 40 arm of the device and means for oscillating it.

In the example of my invention illustrated by the drawings, 1 indicates a grotesque figure representation of a human being constituting a trunk 2, an oscillating head 3, arms 45 4, 5 and legs 6; the arms and legs being loosely pivoted to the trunk 2, whereby they have free swinging movement.

The head 3 is in pivotal engagement with the pivot 7 which carries the arms 4 and 5, 50 and its neck part is provided with a bifurcated extension for engagement with a lateral pin or stop 3^a, whereby the movement of the head is limited.

The several members of the figure are composed of sheet metal, but I may employ other

materials and use rounded instead of flat members.

Attached to the hand of the arm 4 is a miniature tambourine 8, adapted to produce sound when said arm is oscillated; the hand 60 of the other arm 5, carries a bell 8^a, which rings as the arm oscillates.

The downward swing of the arm 5 is limited by means of a stop 9 extended laterally from the body 2; and the arm 4 bears against 65 a washer 10 mounted on a pivot 11, said arm having a cam-like part 12 for bearing engagement with said washer. The pivot 11 extends through a slot 13 of the body 2, and is carried by an angularly extended standard 70 14 forming part of a socket 15 which is fixed to a handle 16.

Rotatably mounted on a fixed axle 17, which is extended laterally from the socket 15, is a traction wheel 18, whereby the device 75 may be moved over a horizontal plane surface by means of the handle 16.

As a means for oscillating the figure, I employ a compound curved rod 19, which swings on a fixed pivot 20, of the standard 80 14, the upper end of said rod having a lateral extension 21 which passes through the trunk 2 of the figure 1; the lower end part of the rod 19 engages a contractile spring 22 having a normal tendency to carry said lower 85 end of the rod towards the standard 14.

To transmit movement to the rod 19 whereby the figure may be oscillated I provide a lug 23 which forms part of a segment 24 fixed to one face of the traction wheel 18. 90

In operation, as a child moves the toy over any flat surface the traction wheel 18 rotates whereby the lug 23 strikes the lower end part of the rod 19, moving it forwardly 95 against the tension of the spring 22, thus swinging the figure rearwardly and upwardly until the lug passes the lower end of the rod, when the spring acts to move the figure in an opposite direction, the slot 13 permitting of upward and downward movement of 100 the figure whereby the washer 10 may act to oscillate the arm 4, whereby the tambourine may be sounded, the swinging movements of the figure also causing the bell to tinkle, the swinging movements of the trunk also causing the head of the figure to oscillate.

It is manifest that a toy of this character will afford considerable amusement to children and owing to the simplicity of construction it may be manufactured at slight cost. 110

I do not wish to be understood as confining myself to the exact details of mechanical parts hereinabove described, nor to the use of a figure representation of a human being, 5 as I may use miniature representations of animals or other moving objects without departing from the spirit and scope of my invention.

Having thus described my invention, what 10 I claim as new and desire to secure by Letters Patent, is:

1. A toy comprising a miniature figure representation of an animate object, said figure having an oscillatory head, means for pivotally supporting said figure in depending correlation, means for imparting oscillatory movement to said figure and its head, and traction means for supporting and operating the device.

20 2. A toy comprising a miniature figure representation of an animate object having swinging legs and arms, and an oscillatory head, means for limiting the oscillatory movement of said head, a standard for supporting said figure, and a handle extended from said standard, and a traction wheel rotatably engaging the lower end of said standard, and means for transmitting oscillatory movement to said figure from said traction 25 wheel.

30 3. A toy comprising a miniature figure having an oscillating head and swinging arms, said head and arms in pivotal engagement with the trunk of the figure by means

of a common pivot, the neck part of said 35 head having a bifurcated extension, and a stop on the trunk of the figure for limiting the oscillatory movement of the head, the trunk of said figure having a segmental slot, and a standard having a pivot passing 40 through said slot, said standard having an extended handle, and a traction wheel in rotatable engagement with said standard and means for transmitting oscillatory movement to said figure from said traction wheel. 45

4. A toy comprising, a figure having an oscillatory head and swinging arms and legs, said arms carrying sounding devices, the trunk of said figure having a segmental slot, and a standard having a pivot passing 50 through said slot, and a handle extended from the lower end of said standard, and a traction wheel rotatably mounted on the lower end of said standard, said wheel having a lateral lug, and a rod pivoted to said 55 standard and having on its upper end a lateral extension which passes through the trunk of the figure, and a spring for connecting the lower end of said rod to the standard, said lug adapted to move the lower end 60 of the rod against the tension of said spring whereby the figure is swung rearwardly by said lug as the toy is moved over a flat surface.

Signed at New York city, in the county of 65 New York and State of New York this 31 day of Aug. A. D. 1920.

ANICETO R. VISITACION
